SPEED CHANGE MECHANISM

Edgar T. Meakin, San Francisco, Calif.

Application March 2, 1940, Serial No. 321,925

3 Claims. (Cl. 74—125.5)

My invention relates to a speed change mechanism for enabling a change in the rotational speed of a driven member with respect to that of the driving member, and more particularly relates to such a mechanism adapted for enabling control of the feeding of moldable material to an extrusion mill or the like.

In an extrusion mill, moldable material is fed to an extrusion chamber where the same is forced through an extrusion die by the application of pressure thereto, such as by means of rollers or the like.

In as much as the desired rate of feed of material to the die chamber depends upon many factors, such as the size of die openings, the character of the material and the proportions of ingredients entering into such material, and the characteristics desired in the extruded product, it becomes apparent that the rate of feed of material must be capable of fine regulation and control within a substantial range of limits.

It is accordingly an object of my invention to provide an improved feed control for extrusion mills or the like; to provide an improved feed control for the feeding of moldable material to an extrusion mill; to provide an improved speed control which may be of general utility but which is particularly applicable in regulating and controlling the feeding of moldable material to an extrusion mill; to provide a speed control for the feed mechanism of an extrusion mill, which shall impart an intermittent movement to such feed mechanism; to provide an improved coupling capable of transforming continuous movement of a driving member into intermittent movement of a driven member; and to provide a feed control for an extrusion mill or the like, which will enable an operator to regulate the rate of feed of moldable material in accordance with the many factors which determine the desirable rate of feed for such machine.

Additional objects of my invention will be pointed out in the following description of the same taken in conjunction with the accompanying drawings wherein—

Figure 1 is a vertical sectional view, partly in elevation, of a preferred embodiment of my improved speed control shown in combination with a fragmentary illustration of a hopper and screw feed assembly of an extrusion mill or the like.

Figure 2 is a front sectional view of the speed control adjustment end of the mechanism of Figure 1, taken along the line 2—2 of Figure 1.

Figure 3 is a view, in section, taken along line 3—3 of Figure 1.

Figure 4 is a view, in section, taken along the line 4—4 of Figure 1, showing the position of internal components during driving engagement.

Figure 5 is a view similar to that of Figure 4, showing the position of the same components when out of driving engagement.

Figure 6 is a view corresponding to that of Figure 1, but depicting a different embodiment of my invention.

Figure 7 is a front elevational view of the embodiment of Figure 6.

Figure 8 is a view, in section, along line 8—8 of Figure 6.

Figure 9 is a view, in section, along line 9—9 of Figure 6.

Figure 10 is a view, in section, along line 10—10 of Figure 6.

In its broadest aspects, my invention pertains to a speed change coupling between a driving and driven member. The driving member may be a shaft coupled to a source of power, such as a prime mover, while the driven member may be another shaft coupled to a load which it is desired to drive. To one of these members is connected a ratchet, while to the other member there is connected a pawl or a plurality of pawls which are adapted to engage with the ratchet and effect a driving connection between the driving member and the driven member.

Cam means is provided to effect such engagement between the pawl and the ratchet, and the speed change is realized by causing the cam means to bring about intermittent engagement in such a manner that the driven member will be connected in driving connection with the driving member for only a portion of each revolution of the driving member. Thus, if the driven member be rotated through an angle of 10 degrees, for example, for each 360 degree rotation of the driving member, then the driven member will make one complete revolution in response to 36 revolutions of the driving member, and a speed reduction ratio of 36 to 1 will be realized. Such speed ratio may be altered by changing the period of driving engagement between the driving member and the driven member during each revolution of the driving member, and this is provided for in my invention, by so designing the cam means as to render it possible to alter the cam surface characteristics, even to the extent of realizing zero revolutions of the driven member during rotation of the driving member, which corresponds to a speed ratio of infinity, and represents a complete stopping of the driven member.

For a more detailed description of my invention, reference will now be made to the aforementioned accompanying drawings.

In Figure 1 of the drawings, I have shown my improved speed control applied to the feed mechanism 1 of a pellet mill, or similar type of apparatus (not illustrated), wherein moldable material is to be fed to an extruding die at a desired rate of feed. The feed mechanism comprises a hopper 3 having a discharge passage 5. The hopper is mounted on a bracket 7 which in turn is supported upon the framework of the

extrusion mill or the like, to which the material in the hopper is to be fed. In this discharge passage is positioned a feed screw 9 having a hollow shaft 11 in which is fitted and riveted a solid shaft 13 extending through and beyond the bracket 7 and terminating in a reduced end section 15.

A ratchet supporting disk 17 having an integral centrally disposed collar 19, is mounted upon and fixed to the shaft 13 by a rivet 21 at a point just beyond the bracket. This disk 17 is formed with a peripheral flange 23 into which is fitted a ratchet 25 of ring shape. This ratchet is held in position within the flange 23 by a plurality of machine screws 27 at distributed points about the flange periphery.

On the reduced end section of the shaft 13 is mounted a pair of spaced bearings 29 and 31 respectively. One of these bearings 31 is positioned in abutment against the shoulder on the shaft 13 formed by the reduced end section, while the other bearing 29 is positioned adjacent the end of the reduced end section. A hollow drive shaft 33 is rotatably mounted on these spaced bearings, and at the end thereof carries a hub 35 having an integral end flange 37. The hub is keyed to the drive shaft 33. A sprocket 39 surrounds the hub and is bolted to the end flange by means of a plurality of peripherally distributed bolts 41 passing through bushings 42 of rubber or the like mounted in the sprocket, thus providing for a shock absorbing chain drive connection to the hollow drive shaft 33.

At the other end of the drive shaft adjacent the ratchet supporting disk 17, there is fixedly mounted on the shaft, a pawl assembly 43. This assembly includes an assembly cage or housing 45 formed in part by a rectangular end plate 47, one pair of diagonally opposite corners of which, at 49, have been cut off on an angle, while the remaining pair of diagonally opposite corners have been notched out, as at 51. The rectangular end plate 47 is flanged along the remaining portions of its side and end edges to provide integral side and end walls 53 and 55 respectively, and is also provided centrally thereof with an integral collar 57 for mounting on the drive shaft 33, to which it is fixed as by welding or other means.

A cover plate 59 having a shape corresponding to the contour of the end plate 47, has a central opening, enabling it to fit over the mounting collar 57 and abut the upper edges of the side and end walls 53 and 55, and is riveted in its assembled position by a plurality of rivets, including one 61 adjacent each notched corner and one 63 disposed at each end of the housing 45. The location of these rivets has been indicated, for by reason of their respective positions, they are enabled to assume additional functions besides holding the cover plate 59 in position, as will be brought out in the process of continuing the description of the pawl assembly.

Within the housing 45 is disposed a pair of pawls 65. Each pawl constitutes a rectangular bar segment which is positioned longitudinally in sliding engagement along a side wall 53 of the housing, with the ratchet engaging end thereof in its rest position, normally protruding through a corner opening in the housing at 49, between the wall 53 and the adjacent corner 66 of an end wall 55. The pawl is thereby adapted to slide into engagement with the ratchet 25, the adjacent end 66 of end wall 55 acting as an anvil and cooperating with the side wall 53 in guiding the pawl along a linear path to and from the ratchet, as distinguished from an arcuate path. Such linear

movement reduces the necessary operating power, as well as enabling the pawl to maintain an even bearing against the ratchet teeth throughout each period of engagement, thus assuring successful operation with less wear.

The other end of each pawl is provided with an axial bore 67 to receive a pawl spring 69, one end of which is exposed and anchored in a hole 71 formed in one of the aforementioned corner rivets 61. The spring 69 is designed to urge its associated pawl 65 into engagement with the ratchet ring 25 in the absence of any means which will preclude such engagement between the pawl and the ratchet.

A retracting lever 73 fulcrumed at an intermediate point about an end rivet 63 is associated with each pawl by having a tapered end 75 engaging such pawl within a rectangular notch 77 formed in a wall thereof. The other end of such retracting lever protrudes through a notched-out corner of the pawl assembly housing as at 51. To this end of the lever, there is connected a stub shaft 79 which carries a pair of aligned ball bearing mounted rollers 81 and 83 respectively. In one of its extreme positions, this lever serves to hold the pawl out of engagement with the ratchet, while in its other extreme position, it will permit such engagement under the urging of the pawl spring.

A pair of adjacently disposed cam disks 85 and 87 respectively are provided, each in the plane of one of the aforementioned rollers 81 and 83. These cam disks are each formed with substantially similar cam surfaces, each cam surface including a high surface on an arc portion 89 of one radius, and a low surface on an arc portion 91 of a smaller radius. Together the two cam disks provide a resulting cam surface for engagement by the aligned rollers 81 and 83 whereby the movement of the lever 73 is controlled.

One of these cam disks 85 is provided with an integral axial mounting sleeve 93 for mounting the same for relative rotation about the drive shaft 33. The sleeve is of a length enabling it to fit between the pawl assembly housing 45 and the hub flange 37.

The second cam disk 87 is also provided with an integral axial mounting sleeve 95, adapting it for mounting about the mounting sleeve 93 of the first cam disk. The mounting sleeve of this second disk terminates in a frontal mounting flange 97 for attachment to the inner surface of the front wall 99 of a housing 101 which serves to enclose and protect the pawl, ratchet and cam assemblies already described.

This protective housing is formed of front and rear cylindrical sections 103 and 105 respectively, bolted together along contacting peripheral flanges 107. The housing is mounted with its rear wall 108 bolted to the bracket 7, such rear wall being formed with a rearwardly extending reduced section 109 to accommodate a ball bearing assembly 111 for supporting the shaft 13.

Upon the end of the mounting sleeve 93 of the first cam disk 85 adjacent the hub flange 37, there is mounted an adjusting bracket 113 which is fixed to the sleeve by a setscrew 115 or other well known means. This bracket extends up and over the front wall 99 of the housing in spaced relationship thereto, and carries at its upper end a locking pin 117 normally urged by a spring 119 into engagement with a toothed sector 121, mounted on the upper surface of the housing 101 adjacent the front wall. This locking pin has

a handle or grip 123 at its upper end, enabling the pin to be manually withdrawn from locking engagement with the toothed sector. This will permit the bracket to be swung through any desired angle, to be subsequently locked in any desired angular position by releasing the locking pin for engagement again with the toothed sector.

The bracket 113 is provided with an opening or window 125 and a pointer 127 extending into the opening and formed integral with the bracket. This pointer is adapted to register with markings on a suitable scale 129, which is mounted on the front wall of the housing, to indicate the angular position of the bracket in terms of speed change characteristics of the mechanism within the housing.

To give significance to the scale readings, the cam disks 85 and 87 must be properly adjusted. When properly adjusted, the cam surface of the bracket connected disk 85 will be so far out of matching alignment with that of the adjacent cam disk 87 that the resulting surface, upon which the rollers can travel, will represent substantially a complete circle, and this relationship will represent the condition of cam adjustment, when the bracket 113 is at its extreme left position of the scale, as viewed in Figure 2. Any subsequent movement or shift of the adjusting bracket to the right, will tend to bring the cam surfaces of the disks more and more into matching alignment and expose an increasing portion of the cam surface of smaller radius of both disks to the rollers. The extreme positions of the adjusting bracket, as indicated on the scale, are determined by a stop pin 131 fixed in a face of disk 85 and engaging an arcuate slot 133 in the opposing face of the adjacent cam disk 87, such slot having an angular spread equal to the angle within which the bracket 40 adjustments are to be made.

Lubrication of the spaced bearings 29 and 31 of the hollow drive shaft 33, and the mounting sleeve 93 of the cam disk 85 is provided for by forming an axial bore 135 into the end of the reduced shaft section 15 and connecting the space between the bearings 29 and 31 with this axial bore by a radial connecting bore 137 formed in the shaft. The lubricant entering the space between the bearings 29 and 31 may reach the mounting sleeve 93 of the cam disk through a perforation 139 in the wall of the main drive shaft 33. The admission and retention of lubricant within the shaft and bearing spaces is facilitated by the attachment of a lubrication fitting 141 to the end of the shaft, and leakage of lubricant past the front end of the mounting sleeve 93 is precluded by the provision of a sealing ring 143 in the sleeve and in frictional contact with the drive shaft. The location of the bore 135 and fitting 141 on the axis of the shaft 15 has the advantage of permitting lubrication during operation, thus avoiding the necessity of a shut down for the purpose.

In explaining the operation of the speed change mechanism as applied to the feed assembly described, we will first assume the adjusting bracket 113 to occupy its extreme left position designated by the word "stop" in Figure 2, and we will further assume the main drive shaft to be in continuous rotation in response to a chain drive connection to the sprocket 39, as previously indicated. When the adjusting bracket is in this position, the resulting cam surface exposed to the rollers will be substantially a

complete circle. Consequently, as the pawl assembly 48 rotates with the drive shaft 33, the rollers 81-83 will rotate about this surface, holding the levers 78 in retracting position, whereby the pawls will be held or retained out of engagement with the ratchet 25 throughout each entire revolution of the drive shaft. In as much as the pawls cannot effect any driving engagement with the ratchet under these conditions, the driven shaft, and consequently the feed screw connected thereto, will not rotate.

As the adjusting bracket is shifted angularly to the right (Figure 2), the disk cam 85 will be angularly shifted about a common axis with respect to the cam 87 fixed to the front wall of the housing. The resulting cam surface developed through such relative movement of the cam disks will include a portion of each of the disk cam surfaces of smaller radius, thus enabling each pair of rollers, as they travel over this resulting cam surface, to drop to a position bringing them closer to the axis of the rotating assembly. Such freedom of movement of the rollers will permit the associated pawl spring 69 to urge its pawl into engagement with the ratchet 25, and such engagement will continue so long as the smaller radius portion of the resulting cam surface is being ridden by such rollers. Thus, each pawl will effect engagement with the ratchet during each revolution of the drive shaft, when the roller associated with that particular pawl is riding a low portion of the resulting cam surface, and the driven shaft will accordingly be rotated a portion of a revolution for each full revolution of the drive shaft, such portion being equal to twice the angle through which each pawl rotates the driven shaft. In as much as the period of engagement between the pawl and ratchet may be altered by adjustment of the adjusting bracket, it will readily be apparent that the ratio between the R. P. M. of the drive shaft and that of the driven shaft may be arbitrarily changed through a substantial range merely through adjustment of the adjusting bracket; and accordingly the rate of feed of the moldable material in the hopper may be adjusted to suit conditions.

In the second embodiment of my invention as illustrated in Figures 6 through 10 inclusive, the speed control mechanism is enclosed within a housing 145 formed of telescoping sections 147 and 149 held together by the bolts 150, with the rear section 149 telescoping within the front section 147 of the housing. The feed mechanism 151, including the hopper 153 and the discharge passage 155, is bolted to the rear wall 157 of the housing. The screw feed element 159 in the discharge passage has a solid shaft 161 axially extending through the housing 149, and is supported within a bearing 163 carried by the rear wall of the housing in an integral collar 165 formed thereon for the purpose. Within the housing and adjacent the rear wall, a collar 167 keyed to the shaft 161, carries a pair of similar radially extending brackets 169. These brackets serve to carry and support the ratchet mounting disk 171 to whose rear surface is affixed a pair of angle brackets 173 which are bolted to the aforementioned collar brackets 169. The ratchet 175 is ring shaped, as in the first embodiment described, and may be retained on the ratchet disk 171 in similar manner.

The drive shaft 177 fits over the end of the screw shaft 161 in abutment against the collar 167 and is held in position by a collar 168 fixed to the end of shaft 161. At the forward end of

the drive shaft a sprocket 178 is keyed thereto, enabling a chain drive connection to the drive shaft. At the collar abutting end, the drive shaft is of reduced section, to accommodate the pawl assembly 181 which is keyed thereto for rotation with said shaft.

This assembly includes a relatively narrow, diametrically positioned base plate 183 having an integral mounting collar 185, whereby the same may be keyed to the drive shaft. The ends of the base plate are notched back to the collar at an angle to the radius and in a direction causing the edge end of the notch 187 formed thereby, to trail the collar end during the normal rotation of the pawl assembly 181, in the direction indicated by the arrow in Figure 10. A pawl 189 is slidably fitted within each of these notches, and has a ratchet engaging end 191 which is normally urged in the direction of the ratchet 175 by a pawl spring 193 inserted under compression between the pawl 189 and the collar end of the notch. A stub shaft 195 extends laterally from each of the pawls, and is adapted to carry a cam engaging roller 197. Each pawl 189 is retained in position in its associated notch by a pawl retaining plate 199 which is formed with an aligned notch 201 of less extent, to permit for movement of the stub shaft 195 in accordance with the sliding movement of the pawl, and thereby permit proper operation of the pawls in accordance with the control exercised by the cam means to be described.

In this embodiment, as in the first embodiment described, the movement of the pawls is controlled by a cam surface resulting from the adjustment between two cam surfaces which together cooperate to provide a resulting cam surface against which the pawl rollers ride. The fixed cam element in this embodiment constitutes a flange 203 extending inwardly from the telescoping end of the rear section of the housing, and having a cam surface formed along its inwardly directed edge.

The adjustable cam element comprises a disk 205 within the housing, adjacent the front wall, and having an integral axial sleeve 207 for mounting about the drive shaft, this disk being provided with a peripheral cam flange 209 terminating adjacent the cam edge of the fixed cam component 203.

An adjusting bracket 211 is keyed to the mounting sleeve 207 of the adjustable disk cam 205, and extends up the front wall of the housing in spaced relationship thereto. This bracket is perforated to provide an opening 213 at a point opposite the outer circular edge of the front wall, and carries a locking pin 215 which is affixed to the front surface of the adjusting bracket and extends through the opening to resiliently engage a toothed sector 217 affixed to the front wall of the housing around the upper half thereof. The locking pin is formed to provide a finger grip portion 219 to release the pin from locking engagement with the toothed sector and permit movement of the adjusting bracket.

The cam surfaces of the cam members, like in the first embodiment, each have a high and low cam surface 221 and 223 respectively, and these cam members are adjusted so that together they provide a substantially circular surface for guidance of the pawl rollers, when the adjusting bracket is at one extreme position indicating total disconnection between the driving end of

the speed change mechanism and the feed mechanism.

The operation of the mechanism is quite similar to that of the first embodiment, in that movement of the adjusting bracket 211 will shift one of the cam elements 205 with respect to the other 203 to expose to the rollers varying proportions of the low and high cam surfaces, whereby the pawls may be caused to engage the ratchet 175 and rotate the feed screw 159 for different periods of each revolution of the drive shaft 177, in accordance with the adjustment of the adjusting bracket.

It will be apparent from the above described embodiments of my invention that they fulfill all the objects set forth by me. While I have described these two embodiments in great detail, it is apparent that they are susceptible to changes and variations, without departing from the spirit of my invention, and I accordingly do not desire to be limited in my protection to the details as disclosed and described by me, except as may be necessitated by the prior art and the appended claims.

I claim:

1. In combination, a pair of cam surfaces, each including an arc section of a particular radius and an arc section of a different radius, means for supporting said cam surfaces adjacent each other with corresponding arc sections in substantial alignment whereby each cam surface is utilizable in its entirety, means for adjusting one of said cam surfaces with respect to the other about a common axis to reduce the utilizable portion of one of said arc sections of each of said cam surfaces to the point of obliteration of such utilizable portion, and means for coupling a driving member and a driven member in accordance with the adjustment of said cam surfaces, said means including a ratchet connected to one of said members and a pawl assembly connected to the other of said members, said pawl assembly comprising an assembly housing having an open corner bounded by a side wall and an end wall of said housing, a pawl in said housing positioned in sliding engagement along said side wall and having its ratchet engaging end protruding through said corner opening in contact with the adjacent edge of said end wall.

50 2. A pawl assembly comprising an assembly housing having an open corner bounded by a side wall and an end wall of said housing, a pawl in said housing positioned in sliding engagement along said side wall and having its ratchet engaging end protruding through said corner opening in contact with the adjacent edge of said end wall.

3. A pawl assembly comprising an assembly housing mounted upon a shaft passing centrally therethrough, said housing having openings facing outwardly away from said shaft, a pair of parallel guide surfaces provided in said housing adjacent each of said openings and offset with respect to the center of said shaft, a pawl having the general form of a rectangular bar segment positioned for linear sliding movement between said guide surfaces, with its ratchet engageable end facing its associated opening in said housing, and means exerting a continual thrust against the other end of each of said pawls tending to force said pawls through said openings along the path of such linear sliding movement and away from said shaft.

EDGAR T. MEAKIN.
